UNITED STATES PATENT OFFICE.

DELOS A. SMITH, OF LOCKE, MICHIGAN.

ADJUSTABLE STOVE-PIPE.

SPECIFICATION forming part of Letters Patent No. 278,617, dated May 29, 1883.

Application filed March 5, 1883. (No model.)

To all whom it may concern:

Be it known that I, DELOS A. SMITH, a citizen of the United States, residing at Locke, in the county of Ingham and State of Michigan, have invented certain new and useful Improvements in Adjustable Stove-Pipes, of which the following is a specification, reference being had therein to the accompanying drawings.

10 This invention has relation to improvements in stove-pipes, and has for its object the adjustment of two or more sections of the pipe together any desired length necessary and at any point required, and firmly holding them together when so adjusted; and with this object in view the invention consists in the novel construction and arrangement of the several parts, as will be hereinafter more fully described.

15 20 The annexed drawings, to which reference is made, fully illustrate my invention, in which—

Figure 1 represents a side view of two sections of stove-pipe, showing my improvement applied thereto. Fig. 2 is a vertical sectional view of the same, and Fig. 3 is a detail sectional view.

25 Referring by letter to the accompanying drawings, A and A' designate two cylindrical sections of a stove-pipe, the section A' telescoped or sliding within the section A, and having near one end a row of perforations, a a a a. The section A' is inserted within the outer section, A, for the purpose of securing it to the outer section, as will be further herein-after explained. The outer section, A, has also holes or perforations a' a', near its end, which, when the two sections are connected, will come in alignment with the holes in the inner section, through which pass pins B B', that are secured to the ends of a flat double spring, C. This double spring C is re-enforced at its center by a piece of metal, c, to give it firmness and rigidity at that point, so that the ends of said spring, where the pins B B' are secured, may have sufficient elasticity to automatically connect the two sections of pipe as the same are slid one within the other.

Any number of holes may be used that is

necessary in putting up stove-pipes of various 5c lengths.

The spring C above described, with its reinforcing piece c is rigidly secured to the outer section near the connecting end by a rivet, which also passes through the metal piece c, as 55 shown in the drawings.

It will be observed by reference to the drawings that the ends of the pins B B' are beveled in opposite directions to one another, which permits either end to operate automatically 60 when the pipes are adjusted.

In taking the sections apart it can be easily accomplished by withdrawing the upper pin only, when the inner pipe can be readily detached from the outer pipe, and in connecting 65 the pipes the lower pin is withdrawn, thus permitting the inner pipe to slide therein. In either movement it will be seen that the pins act automatically in locking the pipes.

From the foregoing description it will be 70 obvious that the operation of my invention is such that it requires but little time in connecting the pipes, and at the same time it is cheap to manufacture.

Having described my invention, what I 75 claim, and desire to secure by Letters Patent, is—

1. The combination, with the pipe-sections A A', having perforations a a', of the double spring C, having re-enforced piece c, and provided with bevel-pins B B', engaging the perforations a, whereby the sections of the pipe are automatically locked together, as shown and described.

2. In combination with the pipes A A', having 85 perforations a a a a', the double spring C, provided with the re-enforcing piece c, secured at its center to the outer pipe, A, both ends adapted to engage by their pins B B' the perforations, whereby the sections are locked together, as shown and described.

In testimony whereof I affix my signature in presence of two witnesses.

DELOS A. SMITH.
